UNITED STATES PATENT OFFICE.

ERNESTO CURTI, OF MILAN, ITALY.

APPARATUS FOR GENERATING, CONTROLLING, AND UTILIZING AIR CURRENTS.

Application filed December 28, 1923, Serial No. 683,254, and in Italy January 8, 1923.

The invention consists in generating, transmitting and utilizing in special machine tools, violent pressure air currents of instantaneous character and slow suction air currents separated by stationary periods; or slow pressure air currents and instantaneous suction currents, all of which phases may follow one another in any desired sequence as required for the operation of the tools concerned.

The succession of the said phases, which may be determined at will, enables the achievement of the following main objects:

A violent pressure followed by a slow suction and by a likewise short stationary period permits of obtaining an efficient powerful blow even with an engine running at a low number of revolutions per minute; of causing the hammer to rise without thumping against the top end of the cylinder; and of fully restoring the air pressure in the piping connecting the tool to the generator.

A slow pressure followed by a sudden suction and by a long stationary period permits of a good working of such tools as require a heavy striker, such as hammers, pestles and the like working by gravity.

A violent pressure followed by a sudden suction and a long stationary period permits a good working of high speed tools. If, however, the striker of said tools is heavy, a quick pressure followed by a slow suction without any stationary period will prove more suitable.

By inserting a valve at any desired point in the connecting piping between the generator and the tools, the valve checking the air flow only in a given direction or in the opposite one, the piping portion comprised between the said valve and the tool will be traversed only by a current of pressure air or only by a current of rarefied air; and a continuous air flow between the generator and the special tools will be realized without need of installing any intermediate air vessel. In this manner the losses due to heating of the air will be avoided and a maximum efficiency secured.

From the foregoing it will be apparent

that the invention secures the following advantages:

(1). The arrangement can work on small air volumes and yet supply an efficient hammering action even when the generator is running at a low number of revolutions; hence a minimum consumption of motive power.

(2). Tools and generators of minimum size can be used, with short stroke and small weight, and consequently less cumbersome. These features ensure a wide field for the most varied applications.

The annexed drawings illustrate, by way of example only, method and means for carrying the invention into execution.

Figs. 1 and 2 show the air current generator in longitudinal section and side view respectively.

Figs. 3, 4, 5 and 6 show cams of various profiles for actuating the generator piston.

Fig. 7 is a longitudinal sectional view of a tool specially adapted for stone chiselling.

Figs. 8 and 9 illustrate two types of pressure regulating valves.

Fig. 10 illustrates a ramming tool used for concrete work, road making and the like.

Figs. 11, 12, 13, 14 illustrate an apparatus specially adapted for drilling rocks etc.

Fig. 15 illustrates an apparatus specially adapted for drilling machines.

Fig. 16 illustrates a compressor with two pump barrels.

Fig. 17 illustrates a high power striking tool.

Fig. 18 illustrates a high speed apparatus working as a hammer.

Figs. 19, 20, 21 show another apparatus with revolving tool.

Figs. 22, 23 show tools directly coupled up to the generator.

Figs. 24, 25 show a modified form of the generator, in which the spring operating the upward stroke of the piston is dispensed with.

The generator (Figs. 1 and 2) comprises:

A shallow cylindrical chamber 1 arranged, for instance, vertically and formed in the machine base on which also the driving elec-

tric motor is erected. In the chamber 1 reciprocates a piston 2, in whose hollow piston rod is lodged a helical compression spring 5, the spring action being adjustable by means 5 of the screw-cap 6. The opposite end of the spring 5 bears against the top end of the chamber formed in the piston rod. The spring 5 accordingly tends to force the piston against the ceiling of the chamber 1, the 10 piston rod 2 projecting through the said ceiling and reciprocating in a packing gland. The bottom of the chamber 1 is provided with large openings 11, so that atmospheric pressure is exerted on the lower face of the 15 piston 2. The piston receives a reciprocating movement, so that in the upper closed portion of the chamber 1 compressions and expansions are alternately set up. At the end of each downward stroke atmospheric 20 pressure is restored through openings 11. The upward stroke is caused by the spring 5, whereas the downward stroke is caused by the motor, through a cam 10 fitted on an extension of the motor shaft and actuating the 25 top end of the piston rod through a roller 7 carried by an arm 8 pivoted on the bracket 9. 11 is a bleed passageway. The length of the piston stroke will obviously be given by the difference between the minimum and the 30 maximum cam radius, and the piston movement will conform to the cam profile, so that during a cam revolution:

The piston may have stationary periods in correspondence to a cam portion whose 35 profile is concentric to the axis of the cam shaft;

The piston may move in a sudden, jerking 40 way in both directions and through the full stroke length in correspondence to steps in the cam profile;

The piston can perform more than one 45 stroke during a single revolution of the cam and these strokes may be of the same or of different lengths.

So for instance the profile of the cam 10 shown in Fig. 3 will cause the piston 2 to make a practically instantaneous upward stroke owing to the nose *a*, and a downward stroke at a uniform and consequently slow 50 speed, due to the spiral portion *b*.

The profile of the cam 10' according to Fig. 4 causes the piston to make a practically instantaneous upward stroke due to the nose *a'*, and a relatively slow downward stroke 55 due to the spiral 'key' *b'* followed by a stationary period at the bottom end of the stroke due to the concentric portion *c'*, the duration of the stationary period being slightly in excess of a half revolution of the cam shaft.

The profile of the cam 10" according to Fig. 5 is adapted to cause the piston to make a downward stroke at a gradual speed owing to the double spiral portion *b''* during 60 one complete revolution of the cam, the said

stroke being followed by a stationary period owing to the concentric portion *c''* lasting for about half a revolution of the cam.

The profile of the cam 10'" according to Fig. 6 causes the piston to make a double 70 stroke at a gradual speed for each complete revolution of the cam, owing to the symmetrical portions *d* and *d'* and the noses *a'''*.

Fig. 7 shows a tool specially suitable for stone and marble chiselling, plate caulking 75 and the like. The cylinder 16, in which plays the striker 17 actuating the underlying chisel, is fitted at the top with a handle 13 and a lever 14 operating a member 15 by which the inlet of the piping 12 is controlled. The striker 17, when nearing the end of its upward stroke, gently engages the elastic cone 18 and is then brought to stop. When an instantaneous pressure comes, the striker is disengaged from said elastic stop and 85 driven with full force downwards against the underlying chisel. A valve provided above the elastic cone 18 enables air to pass from the outside into the tool in order to fill the piping 12 during all the time the 90 generator remains inoperative.

In some cases it may be required that the pressure or depression, though practically instantaneous, yet shall be lowered just before they cease. In such cases an adjustable valve opening inwardly, or reversely, is fitted to the pump barrels. By way of example two valve types, one single-acting and the other double-acting, are shown in Figs. 8 and 9 respectively for the said purpose. They 95 may be fitted either on the tools, or on the connecting pipings or on the pump barrel or chamber outlet. As closing member in the valve, an annular flexible double diaphragm 56—57 is provided. When lying in its normal position, the diaphragm closes a circular set of holes 22—23, either totally or partially. When deflected, it uncovers the said holes and thereby causes the piping to communicate with the atmosphere as a consequence 110 of a rise or of a fall of the inner pressure relatively to the outer pressure.

In the ramming device for concrete work, road making and the like according to Fig. 10, 26 is the flat beater, 24 the cylinder, 27 the cover to which a handle (not shown in the figure) is fitted, 25 is the piston with the long piston rod 25' required in this special case. The impulse pressure from the generator forces the flat beater or ram 26 downwards and thus compresses the concrete, road bed etc. concerned. The following generator depression causes 25 and 26 to rise and prepares for the next downward stroke. A regulating valve is fitted at 29 (Fig. 10) and a further valve 29 of the same type is fitted to the generator at any convenient point (Fig. 1). The former valve serves to let a small amount of air escape after the members 25 and 26 have been 125 130 135

lowered, in order that the pressure existing above the piston 25 may not hinder the formation of the vacuum required for its next quick upward stroke. The latter valve 5 serves to facilitate the restoration of atmospheric pressure in the generator at the end of each stroke.

Fig. 11 represents an apparatus utilizing the impulses supplied by the generator 10 across the connecting piping 120. This apparatus is specially intended for rock-drilling and accordingly comprises a drill which automatically rotates about its axis. In the cylinder 48 is arranged a rotatable 15 tube 32, fitted with an enlarged bottom end (Figs. 11 and 14). The cylinder 48 (Figs. 12 and 13) has two channels 36 and 42 divided into two chambers by the vanes 37 and 43 rigidly secured to the tube 32. The same 20 air impulses that cause the striker 34 to rise and fall and therewith to deal blows on the drill head, enter the channels 36—42 and by impinging against the said vanes, cause them to swing like a piston in a revolving 25 cylinder. A ratchet gear comprising the pawl 46 and the compression spring 50 (Fig. 13) transmits the swinging motion of the vanes to the ratchet wheel 47 and to the drill rigidly secured therein. The air from 30 the generator also enters the channels 31, and the cylinder 32 communicates with the said channels through the holes 33. Accordingly, if the striker 34 is in its highest position, it will be violently forced downward against the drill head. The air will then enter the channel 36 through the hole 35, this hole being uncovered when the striker has reached its lowest position. This air will impinge against the vanes and make 35 the cylinder or tube 32 turn until the holes 33 are covered and the holes 38 uncovered, whereby the channels 31 will be placed in communication with the portion of the tube 32 lying below the underside of the striker 40. The hole 39 will be placed into communication with the hole 40 and thus permit the air that has remained in the tube 32 above the striker 34 to escape to the atmosphere. The air that has rushed into 45 the cylinder 32 through the holes 38 will force the striker upward and bring it back to its starting position. The striker in moving upward will uncover the hole 41 and thus cause the air to enter the channel 42 and impinge again the vane 43. In this manner also the tube 32 will be restored to 50 its starting position, that is to say, with the holes 33 in communication with the channels 31, and the holes 38 covered. Furthermore 55 the tube 32 will block off the communication between the ports 39 and 40, and establish it, instead, between the ports 44 and 45 in order to permit the escapement of the air from under the striker 34 so as not to hinder 60 the next downward stroke of the striker. 65

Fig. 15 diagrammatically shows an apparatus in which the working tool is fitted with rotating mechanism alone. This is the typical case for drilling machines. The apparatus is substantially identical with the preceding one, the only difference being that the striker is used only as a distribution and not as a striking means. The said member is therefore held between two helical springs 31 that are so adjusted as to permit 70 it to oscillate only just as much as is required to distribute the impulses supplied by the generator.

Figs. 16 and 17 show an apparatus for use when a high amount of striking energy is required. The apparatus works similar to the type illustrated by Figs. 1 and 7, but with two pipings 62 and 63 leading respectively from the top and bottom halves of the same generator chamber 60. This chamber has two air bleeds 11 and 61, and the pipes are connected to the chamber by nipples 65 and 66.

Fig. 18 shows a tool working as a high velocity hammer, with two continuous air currents and with a distributor. The apparatus comprises a cylinder 70 connected to another cylinder 70'. Cylinder 70' actuates a distributor 68, whereas in the cylinder 70 reciprocates a striker 71 to which a rod 71' is attached. The upper portion of the cylinders 70—70' is fitted with a cover plate 75. The continuous air current from the piping 67 enters the chamber 70' of the distributor 68 and forces the distributor downwards, thus establishing a communication between the inner port 72 and the outer port 73. In this manner the air entrapped in the cylinder 70 under the striker 71 is allowed to escape to the atmosphere. After this a communication will be established through the port 69 between the air supplied by the pipe 67 and the space above the striker 71. The air impinging against the striker 71 will cause it to deal a sharp blow to the work. In this phase, the generator compresses the air and works in conjunction with the pipe 67, while the piping 68' is inoperative, so as to overcome the eventual resistances to the downward swinging of the distributor 68. In the next phase the generator sets up a stationary phase in the piping 67 and a pressure phase in the piping 68' and allows the distributor 68 to rise and revert to its former position. The hole 72 will let air into the cylinder 70 below the striker 71, thus forcing the striker upwards. The hole 69 will communicate with the external hole 74 and permit the air in the space above the striker 71 to escape to the atmosphere. The valves 76 and 77, serving to render the air flow a continuous one, may be fitted at any desired point of the pipings 67 and 68' and are of the pattern described above.

Fig. 19 shows another tool fitted with a revolving distributor and adapted to work also at considerable distances. The apparatus comprises a cylinder 81, having a bottom 82 and a cap 83. The air is delivered into the cylinder by the piping 90 and is controlled by the distributor 84. Within the cylinder 81 reciprocates the striker 85 formed integral with the rod 85'. When the parts concerned are in the position shown in Fig. 19, special ducts provided inside of the rod 85' allow the air existing in the cylinder space below the striker 85 to pass into the chamber 87 and thence, through 88', into the chamber 90' of the cap 83, where it impinges on the vane 89 forming part of the distributor 84 (Figs. 20-21). The distributor at this moment will be in the position shown in Fig. 21 and the hole 91 for the top inlet will not register with the hole 92 in the cylinder end, thus closing the air inlet and preventing the air outlet through the hole 93, because this hole does not register with the hole 94 nor with the hole 104 opening to the atmosphere. On the contrary there are open the lower inlet hole 95 and the upper outlet hole 97. The hole 95 registers with the hole 96 formed in the cylinder plate, and the hole 97 communicates with the corresponding cylinder and the external hole 105. I wish to point out that only the inlet holes 91-95 are in communication with the air delivered by the piping 90. The outlet holes 93-97 are alternately set in communication with the atmosphere through the holes 104 and 105 formed in the outer periphery of cover 83. Accordingly, the air impinging upon the vane 89 will force it and cause the distributor to revolve so as to bring the holes from the position shown in Fig. 20 into the position shown in Fig. 21. The upper inlet hole 91 now registers the hole 92, and the lower outlet hole 95 registers the corresponding hole 94. The lower inlet hole 95 and the upper outlet hole 97 are closed since they do not register with the corresponding holes 96 and 98. At this moment air is let into the cylinder 81 and, rushing against the upper face of the striker 85, forces the striker downward so as to impart a blow to the tool, while the air existing in the cylinder space under the striker will have already escaped through holes 102 into duct 103 and thence, through holes 94, 93, 104, to the atmosphere. After administering the blow on the work, the air, finding no open outlet, will rise in pressure until it forces open the valve 99 that opens outwardly. This air will then pass on through the duct 100 and impinge on the other vane 101 of the distributor, thus restoring the distributor to its initial position. The air will now pass, through the hole 95, into the circular passage 103, and thence, through the holes 102, into the cylinder

space below the striker 85. The striker will thus be forced upwards and the air above it will escape through the holes 97, 98, 105. In order to prevent 85 from striking the bottom end 82 of the cylinder 81, the rod 85' has a reduced portion 86, past which, a little before the striker 85 reaches the bottom end of its downward stroke, the air rises to actuate the distributor in the manner already described above. 75

Figs. 22 and 23 show two embodiments in which the tool is coupled to the pump barrel directly. In Fig. 22 the double-acting piston 2 actuates the striker 17 of the tool 16 by means of two pipes. The effect of the pressure supplied by one pump barrel adds itself to the effect of the depression supplied at the same instant by the other pump barrel. In Fig. 23 a single-acting chamber 1 is provided, the same working only on the top face of the striker 17, which is raised and lowered in unison due to the movement of the piston 2. 80

The generator according to the modified form represented by Figs. 24 and 25 is operated without the assistance of the spring 5 and exhibits all the features of the generator already described, the sole difference being that the spring 5 effecting the piston's return to its former position is eliminated. 90 95

The function of the spring in this instance is performed by a slot cam 106 formed in the fly-wheel 110, the said slot engaging a roller 107 secured to the top end of the rod 4 of the piston 2. 100

This slot effects the downward as well as the upward stroke of the piston.

In the chamber 1 reciprocates the piston 2, whose rod 4 has secured to its top end a roller 107. The roller is constantly engaged 105 by a slot cam 106 formed in a fly-wheel 110 keyed to the shaft 109, this shaft being driven by the motor 108 in any convenient manner, for instance through gear wheels 111, 112. 110

The slot cam 106 may be given a great variety of forms so as to impart to the piston 2 different movements in accordance with the requirements of the special applications for which the generator is used. 115

Having now described my invention and how the same is to be carried out, what I claim as my invention is:

1. A generator for producing gas currents in different phases comprising a rotatable cam member, a cylinder, a piston reciprocating in said cylinder, a pipe communicating with the cylinder for placing the cylinder in communication with a gas operated tool, and means including the cam for moving the piston forcibly and rapidly in one direction and for moving it gradually and slowly in the opposite direction. 120 125

2. A generator as claimed in claim 1 in which the last mentioned means holds the 130

piston stationary at one end of the cylinder during a partial revolution of the cam.

3. A generator as claimed in claim 1 in which the last mentioned means includes a piston rod and a spring for forcing the piston rod towards the cam.

4. An apparatus as claimed in claim 1 including a second pipe connected to the cyl-

inder, one pipe being connected to one end portion of the cylinder and the other pipe being connected to the other end portion of the cylinder, whereby the piston is double-acting.

In testimony whereof I affix my signature.

ERNESTO CURTI.
